FILM SPOOL MAGAZINE

Bob Mouissie, Yverdon, Vaud, Switzerland, assignor to Paillard SA., Vaud, Switzerland, a corporation of Switzerland

Filed Dec. 19, 1966, Ser. No. 5,104

Claims priority, application Switzerland June 20, 1966

Term of patent 14 years

(Cl. D61—1)

FIG. 1 is a side, top and rear perspective view of a film spool magazine, showing my new design; and

FIG. 2 is an opposite side, top and front perspective view thereof.

I claim:

The ornamental design for a film spool magazine, substantially as shown.
